UNITED STATES PATENT OFFICE

GÜNTHER MEYER-JAGENBERG, OF DUSSELDORF, GERMANY

BOX-MAKING MACHINE

Application filed April 8, 1927, Serial No. 181,929, and in Germany July 30, 1926.

This invention has reference to improvements in the manufacture of boxes of substantially flexible material and it relates in particular to means of applying pasting pieces of flexible material thereto for reinforcing and other purposes and for applying printed or stamped matter to the box sections or for directly printing and stamping the same or for submitting them to the treatment by means 5 of dies and the like. The box sections in these operations are preferably treated in the well-known manner by circularly arranged printing and stamping instrumentalities mounted on a turntable, the said instrumentalities, 10 dies, pressing and printing means, stamps and the like being operated and controlled in accordance with this invention from a cam roller which is so arranged and constructed that it will participate in the partial movements 15 of the turntable or the like carrying the printing or pressing means, while after each individual partial rotation the cam roller will return to its initial position which results in the lowering of the printing or pressing 20 means, plunger or the like at the feeding station of the box sections and the simultaneous raising of the plunger or the like on the stations operating as ejecting means, while the 25 pressing and printing instrumentalities which happen to be in the printing or stamping position will not be operated. It is another object of this invention to provide a safety appliance in connection with the other instrumentalities, by means of which the admission 30 of a piece or slip of coating paper which acquires adhesiveness by heat to the charging station of the box sections is prevented, in case of deficient feeding of a box section from any reason, so as to obviate the possibility of a 35 piece of coating paper or the like being forced into an empty matrix and adhering to the pressing die or the like.

The invention will be further described by reference to the accompanying drawing 40 showing by way of exemplification a preferred embodiment of the principles thereof, Fig. 1 is a vertical section thru the device with lateral box-admitting means. Fig. 2 is a vertical section on the line 2—2 through 45 the device according to the exemplification

of Fig. 1. Fig. 3^a is a plan view showing one of the matrices and the means for feeding a paper wrapper thereto. Figs. 3 and 4 are horizontal sections on the lines 3—3 and 4—4 respectively of Fig. 1. In Figure 55 5 another vertical section is shown on the line 5—5 of Fig. 1. Fig. 6 is a detail section on line 6—6 of Fig. 5. Figs. 7, 7^a, 8 and 8^a are views illustrating the actions of the box body feeding, holding and releasing 60 devices and means controlling the same. Fig. 9 is a view of the suction feed device and co-acting parts. Fig. 10 is a box-section before the pasting and pressing operation. Fig. 11 shows the box-section after the parts have 65 been united by pasting and pressing. Fig. 12 is a fragmentary perspective view of a portion of the machine frame, showing the suction device and grippers for feeding 70 wrappers to the matrices.

Upon the base plate 1 and by means of posts 2 a rotary carrier is mounted comprising a table plate 3 which carries the supports 4 with rollers 5. Upon these rollers the outer marginal portion of a turntable 6 is adapted 75 to rest which is secured to a vertical shaft 7 which is supported on the base plate 1. Above the turntable 6 a cross-shaped skeleton bearing member 9 is arranged the apertures 10 of which serve for the vertical guiding 80 of the rods 11 of the pressing dies or plungers 12 the reciprocation of which in the vertical direction is effected by a cam cylinder 13 in the cam groove 62 of which the free 85 ends of the rods 11 are suspended by means of rollers 14. The cam 13 is retained in position on its top portion by the guide rollers 70. Below the pressing plungers or dies 12 matrices 15 are arranged, each matrix having a supporting stem 15^a slidably engaging 90 the bore of a bracket member 15^b and yielding supported therein by a backing spring 15^c. The heating of the matrices may be effected by gas burners or the like 16. The turntable 6 is operated by means of a train 95 of gearing 66 and by the transmission gearing 17 from a Geneva movement 18 which is driven by a roller 19 (Fig. 2) secured to a bevelled gear-wheel 20. Said gear wheel 20 is in mesh with the bevelled gear wheel 100

21 on the shaft 22 which transmits its movement by means of bevel gear wheels or mitre wheels 58 to a shaft 59 (Fig. 4). On shaft 22 is a gear 22^a receiving motion from a pinion 22^b on a drive shaft 22^c carrying pulleys 22^d or other means for receiving motion from any suitable source of power. A dog or lock bar 24 which is operated by a cam surface of a double cam disc 23 mounted upon the shaft 59 (Figs. 4 and 5) serves for the arresting of the shaft 7 and of the turn table 6, after the feeding of the Geneva wheel 18. On the shaft 22 a cam disc 25 is disposed which, by means of a lever 26, and the vertically disposed transmission shaft 27 carrying said lever operates and controls a toothed segment 28 (Figure 2) which transmits its oscillating movement to a curved rack or gear wheel 29 on the cam 13 and in consequence thereof this cam is compelled to perform an oscillatory movement likewise, that is to say, first the movement in the same direction as the turn-table 6, and upon the reversal of the movement of the segment in the direction opposite to that of the turn-table. A conveyor 30 transfers the box sections 31 to a platform 32 (Figures 1 and 2) from which they are carried across the matrices 15 substantially at right angle to the direction of movement of the apron or conveyor 30 and during this movement they are supported by narrow and spring supported guide bars or the like 33. Laterally disposed with relation to these bars and in front of the conveying apron (according to Figure 1) a pile of enveloping or coating paper 34 is arranged, and at an inclination towards the outside of the machine. A suction feed device 35 for the pulling off of the lowest piece of enveloping paper to be gripped by the tongs 41, as hereinafter described, is rockingly secured on the shaft 36 (Figures 1, 3, 5, 7 and 9) to which upward movement is imparted by means of a lever 37, a bar 38, and a spring 38'', and to which downward movement is imparted through a cam roller 39 from a cam disc 40 on the shaft 59. The suction device delivers the paper wrapper 31' between the tongs or grippers 41, 71. Tongs 41 are mounted on non-circular rods 72 which are rotatably and slidably fitted in bearing eyes 73, 74. On the rods 72, between the eyes 74, are mounted crank arms 75 connected by rods 76 with spring-pressed bell-crank levers 77 carrying rollers 78 which respectively bear against a cam surface of the double cam disk 23, heretofore referred to, and against the cam surface of another cam disk 23', on the rotation of which the tongs 41 are raised and lowered (opened and closed with respect to tongs 71) at proper intervals. The tongs 71 and the bearing eyes 73 are mounted on slide bars 42 which are movable to and fro by

means of rocker levers 42' operated at timed intervals by cam 43 on shaft 59.

In the position of the parts shown in Figs. 1, 3^a and 12, in which the tongs or grippers are in position to receive a wrapper, the tongs 41 are raised by means of the parts 77, 76, 75, 72, whereupon the suction feeder delivers a wrapper onto the tongs 71. The tongs 41 are then lowered so as to clamp the wrapper between them and the tongs 71 and then the closed tongs, carrying with them the wrapper, are moved by parts 42, 42' toward the matrix 15 which is in receiving position until the wrapper lies above and in exact registry with the matrix. At this moment tongs 41 are again lifted, thus releasing the wrapper 34' which drops onto the matrix. Parts 42, 42' then operate to return the tongs to initial position. The box section 31 arriving by way of the conveying apron upon the platform 32 is pushed below the pressing plunger or die 12 and above the anvil or matrix 15 by a slide 44 (Fig. 7) and by the action of a spring 46 acting upon the two-armed lever 45. The movement of the lever 45 is produced by means of a cam disc 47 upon the shaft 59, upon which cam disc the free end of said two-armed lever 45 is adapted to bear. To the slide or push arm 44 a safety device is connected which consists of a locking pin 48 (Figures 5 and 7) adapted to become engaged behind an adjustable lug 50' of a feeler 50 keyed to the shaft 49 and rotatable therewith so that the slide will be locked from movement until the pin is released by the feeler. Further, this feeler 50 acts on a bar 52, with which it is connected by lever 51, which latter is held rigidly on the pivot pin 49 of the feeler. The other end of the bar 52 is mounted on the standard pillar 2 in the slot or bifurcation of a horizontally bifurcated guide member 53, in the top and bottom walls of which are registering cut-outs 54; and on the bar 52 there is provided a corresponding cut-out 54'. Depending upon the position of the feeler 50 the bar 52 is either in the position according to Figs. 7 and 7^a or according to Figs. 8 and 8^a. In the first-named position the cut-out 54' is at one side of or out of registry with cut-out 54, while in the other position the cut-outs 54, 54' register. In Fig. 7^a one finger 38' of bar 38, which latter moves the sucker 35, so contacts with the bar 52 that the finger is held in its lowermost position. But if the bar 52 (Fig. 8^a) is moved to bring cut-outs 54, 54' into registry, then finger 38' can pass through cut-out 54' of bar 52 upwardly. If, then, feeler 50 is moved through a box 31 in upward direction (Fig. 8) and the cam disk 40 releases the rod 38, then the spring 38'' will pull the rod 38 so far upwardly, that the finger 38' engages in the cut-out 54' and the sucker 35 is moved over toward the pile 34. If a box

fails to arrive, then the feeler likewise will remain in the position Fig. 7, the cut-out 54' being out of registry with the cut-outs 54 of guide 53. If now the rod 38 is released from the cam disk 40, then it is prevented from ascending because finger 38' contacts with bar 52, the sucker 35 remains in its position of rest and no cover paper is withdrawn from pile 34. Another slide or push arm 55 (Figure 2) parallel to the slide 44 and operated by a system of levers 67 serves for the ejection of the finished box portions. The said arm carries fingers or the like 56 (Figure 2) on the lateral arms 68, which in the operative position are disposed above the frame of the die or matrice 15 and push the box portion off the same upon the raising of the pressing die or plunger 12. An angle piece 57 (Figure 2) secured to one of said arms 67, leads the box to be delivered onto an inclined chute or piece of sheet metal 69. The operation of the device described is substantially as follows: The prepared box sections 31 are conducted by the conveying apron or the like 30 to the platform 32 where they will press against the feeler 50 the locking lug 50' of which will become disengaged and will release the slide or push bar 44. Bars 61 rockingly disposed on the shaft 60 (Figures 1 and 3) are bearing at the same time with their free ends upon the box sections, so that owing to sufficient friction with the conveying apron being produced thereby the reliable feeding forward of the box parts 35 and the release of the feeler arrangement will only take place, when the box section has assumed its proper position with relation to the slide 44. This slide will then push the box section sideways at substantially right angle to the previous direction of movement onto the die or matrice 15 located at the pressing station I where the box section rests upon the spring acting guide bars 33. At the same time a wrapping paper is pulled off the pile by the suction member 35, inasmuch as by the release of the slide 44 the locking of the bar 38 has been discontinued, the said piece of wrapper being placed across the matrice 15 by the tongs 41. The plunger or 40 pressing die 12 is lowered by means of the cam race of the cam 13 and forces the box section 31 upon the wrapping paper 34' (Figure 10), while the supporting bars 33 spring 45 actingly yield in the downward direction. By the use of the heated matrice 15 the pasting of the wrapping or enveloping paper is effected in the usual manner, the paste upon said wrapping paper becoming sticky 50 by heat, and upon continuing the downward 55 movement of the plunger 12 the box parts are pressed together and united (Fig. 11). Under the action of this compressing pressure the box part is moved through the other 60 treating stations II, III, IV. On the last station the compressing pressure is released, 65

the plunger or pressing die is raised, and the fingers 56 of the pusher or slide 55 push the finished box part off the pressing die 12, and the pusher 55 ejects it into the chute 69.

The raised portion of the cam race 62 (Figure 2) moves up and down between the stations I and IV in view of the reciprocating movement of the cam 13, and by this means the compression and the ejection at these stations is produced. The cam 13 participates with the same angular velocity in the partial rotations of the turn-table 6, while after each partial rotation it is rotated back again into its initial position by the segment 28. In this last stage of movement the plunger or pressing die 12 is lowered at the charging station I, and at the ejecting station the plunger is simultaneously raised, whereupon by means of the then following partial rotation of the turn-table 6 together with the rotation of the cam 13 this raised plunger is transferred to the station I. At the stations II and III the pressing dies or plungers 12 remain in their lowered position.

Instead of four stations a greater number thereof may obviously be employed, so that the duration of the pressing operation is extended. Other changes and modifications are also possible within the scope and spirit of my invention, as directed by local conditions and the convenience of the user, and without thereby deviating from the principles of the invention, as expressed in the appended claims.

I claim:—

1. In a box making machine in combination, an intermittently movable rotary carrier, supporting dies for box sections and corresponding pressing plungers engageable therewith and axially movable with relation thereto, means to periodically feed a sheet of flexible wrapping material between the dies and the plungers and in contact with the dies, additional feeding means at an angle to the other feeding means and adapted to feed unfinished box sections into position above said sheet subsequent to the feeding thereof, locking and releasing means for the box-section-feeding means, and ejecting means engageable with the dies and adapted to eject the finished box sections.

2. In a box making machine in combination, an intermittently movable rotary carrier, supporting dies for the treatment of box portions and corresponding pressing plungers engageable therewith and axially movable with relation thereto, means to periodically feed a sheet of flexible wrapping material between the dies and the plungers and into contact with the dies, additional box-portion-feeding means at an angle to the other feeding means, a displaceable feeler, engageable locking means respectively disposed on the feeler and on the box-portion feeding means and releasable by the pressure

- of the box portions thereagainst, guiding and arresting means for the box-portion feeding means, and ejecting means engageable with the dies and adapted to discharge the finished box-portions from said dies.
5. In a box making machine in combination, a periodically moved and arrested rotary carrier, a plurality of supporting dies, spacedly and circularly disposed on said carrier, correspondingly disposed axially movable pressing plungers, adapted for alternating engagement with and disengagement from the dies, a cam for operating the plungers, means to impart oscillatory motion to the cam during part of the movement of the dies and adapted to produce simultaneous engagement and disengagement of different plungers with and from the corresponding dies, means to lock and arrest the carrier between the rotation periods, means to feed a sheet of flexible material onto the carrier and in contact with one of the dies, and means angularly disposed with relation to said feeding means and adapted for the feeding of box portions onto said dies, box-portions admitting means laterally disposed with relation to the box-portion feeding means, a feeler intermediate said last-mentioned feeding means and the admitting means, and an operative connection between said feeding means and the feeler.
4. In a box making machine in combination, a periodically moved and arrested rotary carrier, a plurality of supporting dies, spacedly and circularly disposed on said carrier and rotatable therewith, a cam above said carrier and the dies, a plurality of compressing plungers in axial alignment with the dies and suspended from said cam, means to impart an oscillatory motion to the cam during periods of rest of the carrier, and thereby adapted to cause simultaneous engagement and disengagement with the dies of different plungers, feeding means for a sheet of flexible material laterally disposed with relation to the carrier, other feeding means for box portions arranged substantially at right angle to the other feeding means and spaced therefrom, a conveyor for box portions, a feeler intermediate said conveyor and the two feeding means and operatively connected to the feeding means, locking means on the feeler engageable with the box-portion feeding means and releasable by the movement of the feeler upon the impact of a box-portion thereagainst, and reciprocable ejecting means engageable with the carrier.
5. In a box making machine, the combination of a carrier intermittently movable in a rotary path, dies mounted on said carrier for opening and closing movements, means for opening and closing said dies during periods of rest of the carrier, means to intermittently feed box portions between said dies, and ejecting means for the finished box portions.
6. In a box making machine, the combination of a carrier intermittently movable through a rotary path during successive motion periods with predetermined periods of rest between such motion periods, dies mounted on said carrier for opening and closing movements, and means to close the dies during one period of rest of the carrier and to open them during another period of rest of the carrier and to keep them closed during intermediate periods.
7. In a box making machine, the combination of an intermittently movable rotary carrier, pairs of supporting dies for box portions and corresponding pressing plungers engageable therewith and axially movable with relation thereto, means to successively move the plungers of the pairs of plungers and dies into engagement with the coacting dies during one period of rest of the carrier and to respectively raise them out of engagement in another period of rest of the carrier, and to keep them in engagement with the dies during intervening periods, means to feed a sheet of flexible material between the dies and plungers, and means to feed box sections onto said sheet and in supporting engagement with the dies.
8. In a box making machine, the combination of an intermittently movable rotary carrier, supporting dies for box portions and corresponding reciprocating pressing plungers engageable therewith and axially movable with relation thereto, means to impart reciprocating motion to the plungers during periods of rest of the carrier, means to periodically feed a sheet of flexible wrapping material between the dies and the plungers, and additional feeding means at an angle to the other feeding means and adapted to feed unfinished box sections into position above said sheet and between the dies and plungers, and ejecting means for the finished box portions.

In testimony whereof I affix my signature.
GÜNTHER MEYER-JAGENBERG.
